UNITED STATES PATENT OFFICE.

GEORGE WILLIAM BALLOU, OF NEW YORK, N. Y.

DESIGN FOR A LAMP-SHADE.

SPECIFICATION forming part of Design No. 25,661, dated June 23, 1896.

Application filed May 18, 1896. Serial No. 592,060. Term of patent 14 years.

To all whom it may concern:

Be it known that I, GEORGE WILLIAM BALLOU, of New York, in the county of New York and State of New York, have invented and produced a certain new and original Design for Lamp-Shades or Gas-Globes, of which the following is a specification, reference being had to the accompanying drawing, forming a part hereof.

10 This invention relates to a new and original design for lamp-shades or gas-globes, of which the following is a specification.

15 In the accompanying drawing, the figure is a perspective view of a glass shade or globe embodying my design.

20 The leading feature of my design consists in a circular glass shade having closely assembled parallel longitudinal ribs rising from an opaque skirt surrounding the base of the shade. The interior of the shade has vertical

ribs *a* extending nearly to the top and bottom edges, while the exterior is provided with horizontal clouded or frosted bands *b b* near each end, and a third similar band *c* just below the upper band *b*. The interior ribs *a* showing through the clear glass give the appearance of the staves of a barrel, while the bands *b* and *c* have the appearance of broad hoops.

I claim—

25 The design for lamp or gas shades, substantially as shown and described.

30 In testimony whereof I have signed my name to this specification, in the presence of two subscribing witnesses, this 13th day of May, A. D. 1896.

GEORGE WILLIAM BALLOU.

Witnesses:

H. A. WEST,
CHARLES J. BRECK.
